Be it known that I, EDWIN WALKER, a citizen of the United States, residing at the city of Erie, in the county of Erie and State of Pennsylvania, have invented and produced a new and original Design for Corkscrew-Collars; and I do hereby declare the following to be a full, clear, and exact description of the invention, such as will enable others skilled 5 in the art to which it appertains to make and use the same, reference being had to the accompanying drawings, and to the letters of reference marked thereon, forming part of this specification.

10 Figure 1 is a perspective view of my design for a corkscrew-collar, the leading feature of which consists in the collar having a downwardly-projecting arm thereon. In the accompanying drawings, illustrating my design, A is the upper portion of the 25 collar, having an opening A' therein.

B B are arms projecting downwardly from the upper portion A of the collar. Upon the inner surfaces of these arms B B are inwardly-projecting vertical ribs b b. On the lower 30 ends of the arms B B and integral therewith is a ring C, forming the lower portion of the collar, and projecting downwardly from one side of the periphery of the ring C there is an arm D, having on its inner surface a sharp 35 rib or edge d.

Having thus described my design for a corkscrew-collar, what I claim is—
